UNITED STATES PATENT OFFICE.

ALEXANDER CONSTANTINE IONIDES, JR., AND SIDNEY VICTOR COOKE, OF LONDON, ENGLAND; SAID COOKE ASSIGNOR TO SAID IONIDES.

MEANS FOR CONTROLLING ELASTIC FLUIDS.

Original application filed December 19, 1916, Serial No. 137,885. Divided and this application filed October 31, 1919. Serial No. 334,877.

To all whom it may concern:

Be it known that we, ALEXANDER CONSTANTINE IONIDES, Junior, a subject of the King of Great Britain and Ireland, and residing at 34 Porchester Terrace, London, W., England, and SIDNEY VICTOR COOKE, a subject of the King of Great Britain and Ireland, and residing at 97 Lewin Road, Streatham, London, S. W., England, have invented certain new and useful Improvements in Means for Controlling Elastic Fluids, of which the following is a specification.

This invention relates to means for maintaining a constant relationship between the pressures of two elastic fluids for the purpose of uniting them in determined proportions, and it is of the type in which a movable partition such as a bell or diaphragm by its movement operates valves which control the pressures of the fluids to which the partition is subjected upon its opposite sides, the present application being a divisional application from Serial No. 137885.

In order to have satisfactory regulation in apparatus as above, it is necessary to give the movable partition a sufficiently large area, while at the same time any unnecessary increase of weight must be avoided so that the momentum of the moving parts may be reduced to a minimum; frictional resistance to movement of the parts and the influence of pressure and velocity of the fluids on the valves must also, as far as possible, be eliminated.

The object of the present invention is to provide for the foregoing considerations in a compact and improved construction.

The invention consists in a fluid pressure balancing device for controlling the pressures of two fluids by valve means operated by a partition movable in accordance with the pressures of the said fluids acting on opposite sides thereof, in which valve means for the two fluids are positioned one above the other in an upright casing divided into an upper and a lower compartment by said partition and the valve means for regulating one fluid is connected to and moves upwards or downwards in accordance with the movement of the partition, while the other valve is connected to the partition by suitable direction reversing means, so that the weight

of one valve may be arranged to balance the weights of the other valve and the partition. 55

The invention further consists in the improved fluid pressure balancing device and various features thereof as hereinafter described and more fully pointed out in the claims. 60

Referring now to the accompanying drawings:

Figure 1 is a sectional elevation of one form of apparatus for carrying the invention into effect. 65

Figure 2 is a plan thereof with the top cover removed, and

Figure 3 is a section on the line X—X of Figure 1. 70

In carrying the invention into effect in the form illustrated by way of example, an upright casing or tower-like structure S formed of lower and upper rectangular members a and a' having cylindrical extensions a², a³, connected by means of flanges a⁴ and a⁵, and the whole surmounted by a cover a⁶ is provided with two double-beat valve boxes b and b' arranged with the valves c and c' in line vertically one above the other and at some distance apart. 80

The valve boxes b, b' are preferably formed as separate castings inserted through apertures a⁷, a⁸, in the sides of the tower and flanges b², b³, attached to the boxes by pipe connections b⁴ and b⁵, form a fluid-tight 85 joint round the apertures. The two pipe connections b⁴ and b⁵ have flanges b⁶ and b⁷ upon the outside of the tower to which the pipes supplying the fluids are connected. Upon the opposite side of the tower flanges a⁹, a¹⁰, are provided for the pipes conducting the fluids from the apparatus after their pressures have been regulated by means of the double-beat valves. 90

The suitable double-beat valves c and c' 95 preferably open by a downward movement, and in order to reduce the inertia of the moving parts to a minimum the valves are made as light as possible consistent with the necessary rigidity. One or both valves may be 100 constructed, as shown in the upper part of the figure, of two hollow frusto-conical members c², c³, supported upon a central tube or column c⁴ and braced together by a plurality of tension rods or wires c⁵, evenly distributed around the circumference of the 105

valve just within the seats which are formed on rings c^6 , c^7 , of somewhat stouter section adapted to contact with the periphery of the frusto-conical members c^2 , c^3 .

5 Within the cylindrical central portion of the casing or tower between the two valve boxes is a horizontal fluid-tight partition or plate dividing the casing into an upper and a lower compartment each containing a 10 valve. The partition as illustrated forms the top of an ordinary gas bell d , the sides of the bell being accommodated in an annular tank e having a rim e^9 held between the flanges a^4 , a^5 , and containing a suitable 15 liquid sealing medium such as oil.

The bell d may be of the lightest possible construction and the tank e may be provided with supporting members e' , e^2 , adapted to protect the top of the bell should it be subjected to any undue stress. Apertures e^3 , e^4 , are provided in these members for allowing access of the fluids to both sides of the top of the bell. A chamber e^5 may also be formed beneath the member e' by means of 20 the bottom e^6 and hooded tube e^7 into which liquid may flow if the seal is blown by excessive pressure and from which it may drain back into the tank through the ball valve e^8 .

30 The apparatus illustrated is arranged to control coal or some other rich gas by means of the lower valve and air by means of the upper one. The gas valve c is therefore of considerably smaller diameter than the air valve c' , say in the ratio of about one to three. It is desirable, however, to allow both the valves to have an equal vertical travel for the purpose of maintaining the best balance conditions and under such circumstances the gas valve c is fitted with parabolic or like suitable plugs c^8 , c^9 , extending beyond the seatings into the openings and regulating the amount of cross-sectional area of the valve orifice so that a constant 35 proportion between the distance moved and the area of passageway is maintained at all 40 positions of the valve travel.

In the event of low quality or power gas being used the quantities of gas and air in 45 the mixture are substantially equal and both of the double-beat valves c and c' and their boxes b and b' may be of the same diameter.

The lower valve c is directly connected by a tension member or the like f to the 50 centre of the under side of the movable bell d . This member should preferably only be flexible at two points and should have a guide in order that no pendulum or oscillatory motion may be engendered. From the 55 centre of the upper side of the bell d a double flexible tension member f' is connected to a quadrant g fixed at the centre of a horizontal lever g' positioned above the bell d and supported at its end g^2 by needle points 60 g^3 , one accommodated in a conical or like

cavity and the other in an angular groove or slot upon each side in the fulcrum studs g^4 .

The upper valve c' is suspended by means of a double flexible tension member f^2 passing over a quadrant g^5 fitted upon the end of a horizontal lever g^6 positioned above the upper valve box. This lever is pivoted in the manner hereinbefore indicated at one-third of its length from the end from which the valve is suspended and it is supported by a bar g^7 attached to the valve box b' . From a quadrant g^8 upon the opposite end of the lever g^6 a tension member f^3 is carried downward to a quadrant g^9 upon the 70 end of the lever g' , this member f^3 being preferably a rod having at each end a sufficient length of flexible material such as multiple link chain to accommodate the arcs.

By means of the hereinbefore described 75 system of levers and flexible tension members an upward movement of the bell d results in an upward movement of the lower valve c and a downward movement of the upper valve c' . If, therefore, the pressure 80 of the fluid passing into the lower compartment exceeds the pressure of that passing into the upper compartment and the bell moves upwards as already indicated the lower double-beat valve will be moved towards its seat and therefore check the flow of fluid through the lower half of the apparatus and thus act to reduce its pressure. At the same time, the upper valve will be lowered, thus increasing the area available 85 for fluid to flow into the upper compartment and tending to increase the pressure therein.

By a suitable arrangement of the weights of the two valves, the bell and the levers and connections, the whole system may be 90 placed in a perfect state of balance, and by reducing the moving weights to the smallest possible amount and eliminating as far as possible the friction attending the movement of the parts, the device may be made 95 to operate with very minute pressure differences and to maintain practical uniformity between the pressures of the two fluids issuing from the upper and lower compartments. By varying the weights on the 100 opposite sides of the balance to a suitable extent, any desired ratio between the pressures of the two fluids may be constantly maintained.

Having now described our invention, what 105 we claim as new and desire to secure by Letters Patent is:—

1. A fluid pressure balancing device for controlling the pressures of two fluids by valve means operated by a partition movable 110 in accordance with the pressures of the said fluids acting on opposite sides thereof, in which valve means for the two fluids balanced in relation to the fluid pressures are positioned one above the other in an upright 115

casing divided into an upper and a lower compartment by said partition and the valve means for regulating one fluid is connected to and moves upwards or downwards in accordance with the movement of the partition while the other valve is connected to the partition by suitable direction reversing means, so that the weight of one valve may be arranged to balance the weights of the other 10 valve and the partition.

2. In combination in a gaseous fluid pressure controlling device an upright casing, a movable diaphragm sealed by a liquid joint dividing said casing into two compartments, 15 valves balanced in relation to the fluid pressures controlling the admission of fluids to said compartments, a tension member connecting one valve to said diaphragm, a lever fulcrummed at one end positioned above 20 said diaphragm, a tension member connecting the diaphragm to the centre of said lever, a second lever fulcrummed between its two ends positioned above the valve in the upper compartment, a tension member connecting 25 the last-mentioned valve to one end of said second lever, and a tension member connecting the other end of said second lever with the end of the first mentioned lever.

3. In combination in a gaseous fuel pressure controlling device, an upright casing, a fluid-tight diaphragm dividing said casing into an upper and a lower compartment and movable in accordance with the variations in the pressures in said compartments, an outlet to each compartment, a valve balanced in 35 relation to the fluid pressures in said lower compartment for admitting fluid thereto, a valve similarly balanced for a like purpose in said upper compartment and means whereby said diaphragm moves said valves in the opposite direction to one another so that a constant relationship may be maintained between the pressures of the fluids issuing from said outlets.

4. In combination in a gaseous fuel pressure controlling device, an upright casing, a fluid-tight diaphragm dividing said casing into an upper and lower compartment, and movable in accordance with the variations in the pressures in said compartments, an outlet to each compartment, a valve balanced in relation to the fluid pressure connected to said diaphragm to move in accordance therewith in one of said compartments for admitting 50 fluid thereto, a valve similarly balanced for a like purpose connected by direction reversing means to said diaphragm in the other compartment so that said diaphragm moves said valves in the opposite direction to one 55 another for maintaining a constant relationship between the pressures of the fluids issuing from said outlets and for balancing the weight of one valve by the weight of the other valve and the diaphragm.

5. In combination in a gaseous fuel pres-

sure controlling device, an upright casing, a fluid-tight diaphragm dividing said casing into an upper and a lower compartment and movable in accordance with the variations in the pressures in said compartments, an outlet to each compartment, a double valve balanced in relation to the fluid pressure in said lower compartment for admitting fluid thereto and connected to the under side of 70 said diaphragm to move in accordance therewith, a double similarly balanced valve for a like purpose in said upper compartment and lightly constructed lever means whereby the upper side of said diaphragm is connected to said upper valve so that the valve moves 75 in the reverse direction to the diaphragm.

6. In combination in a gaseous fuel pressure controlling device, an upright casing, a fluid-tight diaphragm dividing said casing into an upper and a lower compartment and 80 movable in accordance with the variations in the pressures in said compartments, an outlet to each compartment, a valve balanced in relation to the fluid pressure in one compartment for admitting fluid thereto, a valve 85 similarly balanced of considerably smaller diameter for a like purpose in the other compartment, means whereby said diaphragm moves both valves the same distance in the opposite direction to one another and a suitably shaped tapering or like plug movable with said smaller valve in the orifice thereof to render the passageway therethrough proportional to the distance which the valve has moved during the entire length of the lift. 90

7. In combination in a gaseous fuel pressure controlling device, an upright casing, a movable diaphragm dividing said casing into two compartments, valves both balanced in relation to the fluid pressures controlling the 100 admission of fluids to said compartments one of said valves being built up of light tubular members braced by light tension rods, a tension member connecting one valve to said diaphragm, and delicately balanced direction reversing means connecting the other valve thereto.

8. In combination in a gaseous fluid pressure controlling device, an upright casing, a movable diaphragm dividing said casing into an upper and a lower compartment, 115 valves balanced in relation to the fluid pressures controlling the admission of fluids to said compartments, means connecting the lower valve to said diaphragm, a lever fulcrummed in said casing, means connecting the diaphragm to said lever, a second lever fulcrummed in said casing, means connecting the valve in the upper compartment to said second lever, and means connecting said 120 second lever with the first mentioned lever.

9. In combination in a gaseous fluid pressure controlling device, an upright casing, a movable diaphragm dividing said casing into two compartments, a valve balanced in 130

relation to the fluid pressures controlling the admission of a fluid to one compartment, a larger valve similarly balanced controlling the admission of a second fluid to the other compartment, means for connecting the smaller valve to one side of said diaphragm, whereby said smaller valve and diaphragm move in the same direction, and means for connecting the larger valve to the other side 5 of said diaphragm whereby said larger valve

and diaphragm move in opposite directions, the force exerted by the weight of the larger valve thus acting in the opposite direction to that exerted by the combined weights of the smaller valve and diaphragm, so as to obtain the minimum amount of moving mass. 15

In testimony whereof we have signed our names to this specification.

ALEXANDER CONSTANTINE IONIDES, Jr.
SIDNEY VICTOR COOKE.
